UNITED STATES PATENT OFFICE.

WILLIAM MILTON KENDRICK, OF WEST CHATHAM, MASSACHUSETTS.

DESIGN FOR AN ELECTRIC CANDLE.

Application filed July 21, 1926. Serial No. 18,443. Term of patent 14 years.

To all whom it may concern:

Be it known that I, WILLIAM M. KENDRICK, a citizen of the United States, and a resident of West Chatham, in the county of Barnstable, State of Massachusetts, United States of America, have invented a new, original, and ornamental Design for an Electric Candle, of which the following is a

specification, reference being had to the accompanying drawing, forming part thereof.

The drawing is a perspective view of an electric candle showing my new design.

I claim:

The ornamental design for an electric candle, substantially as shown.

WILLIAM MILTON KENDRICK.
